SINGLE SIDE BAND AMPLIFIER CIRCUIT

Walter H. Wirkler, Cedar Rapids, Iowa, assignor
to Collins Radio Company, Cedar Rapids,
Iowa, a corporation of Iowa

Original application August 4, 1938, Serial No.
223,096. Divided and this application Sep-
tember 16, 1939, Serial No. 295,311

4 Claims. (Cl. 179—171.5)

My invention relates broadly to an amplification system for single side band waves, and more particularly to a split side band amplifier having means for dissipating undesired side bands. The circuit of my invention is applicable in single side band suppressed carrier transmission systems of the type shown in my copending application Serial No. 176,670, filed November 26, 1937, Patent No. 2,173,145, September 19, 1939, for Single side band transmitter.

This application is a division of my copending application Serial No. 223,096, filed August 4, 1938, for Split side band amplifier circuit.

One of the objects of my invention is to provide means for the selection and efficient amplification of single side band currents, with the carrier suppressed.

Another object of my invention is to provide an amplification system for split side band circuits adapted for single side band systems.

Still another object of my invention is the provision of means for using the bridge circuit principle in splitting double side band currents into two single side band currents.

A further object of my invention is to provide a balanced bridge circuit for deriving single side band currents from sets of double side band components in phase quadrature, for transmission exclusive of the other side band component.

Other and further objects of my invention reside in the circuit arrangement herein disclosed and hereinafter more fully described with reference to the accompanying drawing which schematically illustrates one form of my invention.

The circuit arrangement is generally similar to the corresponding portion of the single side band transmitter of my copending application Serial No. 176,670, above noted.

The drawing shows the modulation and side band amplifier portions of a transmitter embodying my invention of single side band amplification. The source of carrier energy at 1 includes an oscillator and amplifier and the carrier energy is fed on the one hand through phase shifting network 2 to balanced modulator 22, and on the other hand directly to balanced modulator 23, the waves in the different modulators being in phase quadrature. The source of signal modulations, such as a program line at 12, delivers modulation energy to the balanced modulators 22 and 23 through phase shifting networks 5 and 6 and amplifiers 20 and 21, respectively, the modulation waves in the different modulators being 90° out of phase. The carrier energy is suppressed in the balanced modulators and double side bands are present in the outputs thereof, 90° out of phase in the separate circuits.

The modulators are of the type shown in application Serial No. 176,670, with carrier and modulation energy impressed in push-pull rela-

tion on the grids of the tubes, V_{11} and V_{12} in modulator 22, and V_{13} and V_{14} in modulator 23. Blocking condensers C_{12} and radio frequency choke coils H_6 are provided in the grid circuits as indicated, and grid bias in the modulators is supplied from sources D_3 and D_4 as shown.

By the application of the bridge circuit of my invention to the combination of the double side band waves in the outputs of both modulators 22 and 23, interaction or cross modulation in the two circuits is prevented. The plate electrodes in the tubes in each balanced modulator are connected together and to the respective load circuit, 24 or 25, thence in common to the source of plate power G_2 , through radio frequency choke coils H_7 . The load circuits 24 and 25 are inductively coupled to opposite diagonal terminals of bridge circuit 26. Two arms of the bridge are formed by capacitances C_{13} and C_{14} , a third by the load presented by the class B linear amplifier 27 at 21, and the fourth by a resistor 28 which operates to dissipate the undesired side bands. Amplifier 27 receives the superior or the inferior side bands from both balanced modulators 22 and 23, depending upon whether the outputs of the modulators are subtracted or added in the arm of the bridge comprising the input circuit of the amplifier 27. The bridge circuit 26 is balanced so that no interaction between the balanced modulators 22, 23, can occur. The single side band thus derived and amplified at 27 is fed to the antenna system for radiation.

The theory of operation of the bridge circuit is as follows. Because of the difference in carrier excitation phase for modulators 22 and 23, the outputs thereof are, respectively:

$$I_a = I_1 \cos \omega t \cos \rho t = \frac{I_1}{2} [\cos (\omega - \rho)t + \cos (\omega + \rho)t]$$

$$I_b = I_1 \sin \omega t \sin \rho t = \frac{I_1}{2} [\cos (\omega - \rho)t - \cos (\omega + \rho)t]$$

The currents I_a and I_b are split into two portions in bridge circuit 26, the components in the input to amplifier 27 being added, for example, while the components in the resistor 28 are subtracted, thus:

$$\frac{I_a + I_b}{2} = \frac{I_1}{2} \cos (\omega - \rho)t = I_s \quad (1)$$

and

$$\frac{I_a - I_b}{2} = \frac{I_1}{2} \cos (\omega + \rho)t = I_u \quad (2)$$

where I_s indicates the inferior side band and I_u the superior side band.

While I have disclosed my invention in a preferred embodiment, I do not intend to be limited specifically thereto, and it is to be understood that modifications may be made within the scope of the appended claims.

What I claim as new and desire to secure by Letters Patent of the United States is as follows:

1. A split side band amplifier including a bridge circuit, means for supplying said bridge circuit at both pairs of opposite terminals with double side band energy, carrier and modulation factors in said double side band energy at the pairs of opposite terminals being respectively in phase quadrature, with adjacent arms of said bridge carrying inferior and superior side band components respectively, an amplifier connected with one arm of said bridge for amplifying the single side band component therein, and means connected in an arm of said bridge adjacent the aforesaid arm for dissipating energy of the other side band component.
- 10 2. A split side band amplifier including a bridge circuit, means for supplying said bridge circuit at both pairs of opposite terminals with double side band energy, carrier and modulation factors in said double side band energy at the pairs of opposite terminals being respectively in phase quadrature, with adjacent arms of said bridge carrying inferior and superior side band components respectively, an amplifier connected with one arm of said bridge for amplifying the single side band component therein, and a resistor connected in an arm of said bridge adjacent the aforesaid arm for dissipating energy of the other side band component.
- 15 3. A split side band system including a bridge circuit, means for supplying said bridge circuit at both pairs of opposite terminals with double

side band energy, with carrier and modulation factors respectively in phase quadrature, the double side band energy in arms of said bridge circuit being additive and subtractive respectively, resulting in the former instance in inferior side band components and in the latter in superior side band components, of like phase; amplifier means connected in one arm of said bridge circuit for amplifying the single side band components in the output thereof, and a resistor connected in an adjacent arm of said bridge circuit for balancing said circuit and dissipating energy of the other side band components therein.

4. A split side band amplifier including a bridge circuit, means for supplying said bridge circuit at both pairs of opposite terminals with double side band energy, carrier and modulation factors in said double side band energy at the pairs of opposite terminals being respectively in phase quadrature, said energy being additive in opposite arms of the bridge and resulting in inferior side band currents in said opposite arms, said energy being subtractive in the alternate opposite arms of the bridge and resulting in superior side band currents in said alternate opposite arms, one arm of said bridge having amplifier means connected therewith for amplifying the single side band currents therein, and an adjacent arm of said bridge having energy dissipating means connected therewith for suppressing the single side band currents therein.

WALTER H. WIRKLER.
